CASING FOR BOILERS

Felix Rankin and Herbert Dannemann,
Brooklyn, N. Y.

Application June 2, 1948, Serial No. 30,722

5 Claims. (Cl. 220—4)

1

This invention relates to jackets, enclosures or casings for boilers, hot water heaters, furnaces or the like. It is particularly directed to knock-down collapsible casings for cylindrical boilers or furnaces made of assembled parts.

Knockdown casings for cylindrical boilers were heretofore constructed of sheet metal parts rolled into permanent round shape and assembled together. In accordance with the present invention, the casing is made of a plurality of normally flat, resilient metal panels assembled together and flexed around the boiler.

Another object of this invention is to provide a substantially cylindrical casing of the character described comprising a front panel and side panels made of normally flat resilient sheet metal stock and removable coupling members coupling said side panels to opposite side edges of the front panel, said assembled panels being adapted to be flexed partly around a cylindrical boiler, and a rear normally flat panel flexed round and having side flanges snapped into channels at the outer sides of the side panels, so that the assembled panels will be retained in substantially cylindrical condition around the cylindrical boiler.

Yet a further object of this invention is to provide a casing for a cylindrical boiler comprising a front panel, side panels coupled to the side edges of the front panel, and said assembled panels being adapted to be flexed into round shape, the outer sides of the side panels being formed with outwardly opening longitudinal channels, and a rear panel having inwardly extending flanges at the sides thereof adapted to snap into said channels for completing the casing.

Still a further object of this invention is to provide a casing of the character described including a top circular cover which may fit over the upper ends of the assembled panels.

Yet another object of this invention is to provide in a casing of the character described, a bottom base band extending around the lower end of the casing and provided with means for attachment to one of the casing panels.

A still further object of this invention is to provide in a casing of the character described, a plurality of rear panels, each of which may comprise two parts having overlapping portions and attached together by screws passing through said overlapping portions, and said parts being formed with notches at their inner edges, the notches of the two parts together forming one or more openings through which pipes or the like articles on the boiler may pass.

2

Yet a further object of this invention is to provide a casing of the character described, made to fit a cylindrical boiler formed with an extension, and said casing including a casing part adapted to fit over said extension, and means for coupling said casing part to other panels of the casing.

Still another object of this invention is to provide a boiler casing comprising a pair of co-extensive panels having at their adjacent edges, turned back flanges, and a cleat having at opposite longitudinal edges thereof inwardly turned flanges slidably engaging the flanges of said panels for assembling said panels together.

15 Still another object of this invention is to provide a strong, rugged and durable casing of the character described, and comprising panels which may be shipped flat, and which may be flexed around the boiler at the place where the 10 casing is assembled with the boiler, the construction being such that there is no necessity for rolling the panels into round shape, and thereby permitting shipment of the entire device in a compact package, and also permitting assembly 20 of the device around the boiler quickly and easily, the said panels being formed with pre-cut holes and cut-outs wherever necessary to accommodate pipes, gauges, valves, burner holes, water and steam inlets, drain pipes or any other parts extending from the boiler.

25 Yet a further object of this invention is to provide a casing of the character described, which shall be easy to assemble, relatively inexpensive to manufacture, and which shall yet be practical and efficient to a high degree in use.

30 Other objects of this invention will in part be obvious and in part hereinafter pointed out.

The invention accordingly consists in the features of construction, combinations of elements, 35 and arrangement of parts, which will be exemplified in the construction hereinafter described, and of which the scope of invention will be indicated in the following claims.

40 In the accompanying drawings in which is shown various illustrative embodiments of this invention,

Fig. 1 is a front view of three of the casing panels assembled together in tandem in flat condition;

45 Fig. 2 is a top plan view of the structure shown in Fig. 1;

Fig. 3 is a top edge view of the base in flat condition;

Fig. 4 is a front view of the structure shown 50 in Fig. 3;

Fig. 5 is a top edge view of one of the rear panels;

Fig. 6 is a front view of the panel shown in Fig. 5;

Figs. 7 and 8 are front views of other rear panels;

Fig. 9 is an enlarged cross-sectional view taken on line 9—9 of Fig. 1;

Fig. 10 is a partial perspective view illustrating the joining of adjacent panels by one of the coupling members or clips;

Fig. 11 is a top plan view of the four panels assembled together and flexed into round shape;

Fig. 12 is a front view of the casing embodying the invention around a boiler;

Fig. 13 is a rear view of a casing embodying the invention around a boiler;

Fig. 14 is a partial perspective view illustrating a modified construction;

Fig. 15 is a top plan view of a casing similar to that shown in Fig. 11 and illustrating a modification thereof;

Fig. 16 is a top plan view of a casing similar to that shown in Fig. 11 and illustrating a further modification thereof, and

Fig. 17 is a top plan view of a casing illustrating a modified construction.

Referring now in detail to the drawing, 10 designates a jacket, casing or housing, embodying the invention, for a boiler or furnace 11 of the cylindrical type. The casing 10 comprises generally a front panel 12, a pair of side panels 13 and a plurality of rear panels 14, 15, 16 and 17, a top cover 18 and a base band 19. All of the parts 12 to 17 and 19 may be made of resilient sheet metal such as aluminum or sheet steel.

The front panel 12 is of rectangular shape and is flat normally. It is formed at the sides thereof with inwardly bent or turned back flanges 30 extending throughout the longitudinal extent of the sides of said panel. The panel 12 may be formed with openings 31 and cut-outs 32 and 33, as may be necessary for registry with various type inlets, outlets, cut-outs, holes or fittings on the boiler itself. In other words, one of the openings or cut-outs 31, 32 or 33 is provided in panel 12 wherever something on the boiler will have to project through the panel or where something will have to project through the panel into the furnace. In fact, any of the panels may be formed with pre-cut openings wherever deemed necessary.

The side panels 13 may be similar but symmetrically disposed. Each of the panels 13 may be formed at its inner side with a bent back flange 35 similar to flange 30. The flanges 30 and 35 are so located that when the panels are flexed around a furnace, as will appear herein-after, said flanges will be at the inside of the assembled casing 10. The front panel 12 is assembled with the side panels 13 by means of longitudinal sliding coupling members or clips 36. Each member 36 comprises a central web 37 and inwardly extending flanges 38. The flanges 38 are received between the panels 12, 13 and the flanges 30, 35. Conversely, the flanges 30, 35 are received between the flanges 38 and the webs 37 of members 36. The clips or coupling members 36 may be the full length of the panels 12 and 13. A plurality of tandem coupling members 36 may be supplied for each joint, as shown in Fig. 1. One clip may be slidably slipped in from one end, and the other from the other end. Each of the side panels 13 is formed at its outer side edge with an integral U-shaped offset portion 40.

Each U-shaped portion 40 comprises a flange portion 41 bent back from the panel 13 and a forwardly bent flange portion 42 extending back from the flange 41. Between the flanges 42 and 41 is formed a channel 43.

The panels 12 and 13 are normally flat, but they may be flexed into part-cylindrical shape when assembled with the rear panels 14, 15, 16 and 17.

Panel 14 may be made of two symmetrical parts 45, 46. The parts 45 and 46 have overlapping portions 45a, 46a, attached together by screws 47 passing through said overlapping portions. Said parts 45, 46 are formed with aligned notches 48 and 49 together forming a cut-out or opening 50 to fit around a flue pipe extending from the boiler. At the outer side edges of the panels 45 and 46 are flanges 52 and 53 adapted to snap into the channels 43 of the panels 13. The front panel 12 is first assembled with the side panels 13 by means of the coupling members 36 as shown in Figs. 1 and 2. The assembled panels 12 and 13 are then flexed into part cylindrical shape so that the portions 40 extend radially, with the channels 43 opening outwardly. The panels 14, 15, 16 and 17 are then flexed into part cylindrical shape, and the flanges 52, 53 will then extend radially and are snapped into the channels 43. Due to the inherent resiliency of the panels, the casing will hold together when thus assembled. In other words, panel 14 will hold together the ends of the assembled panels 12, 13. It will be noted that the panel 14 extends from the top of the casing down part way. The panel 15 is the same as the panel 14 except that it is formed with notches 60, 61, 62 and 63. The notches 60, 61 form a hole 64, whereas the notches 62, 63 form a hole 65. The panel 15 likewise snaps on to the ends of panels 13, 14 and is disposed just below the panel 14. Panel 16 may be similarly constructed to panel 15 except that it may only have one opening 66 instead of two openings 64, 65. Panel 16 may fit in place just below the panel 15. Panel 17 which extends from the lower end of panel 16 to the lower end of the casing is made of a single sheet of normally flat resilient sheet metal, and has the ends thereof flanged similarly to flanges 52, 53 for snapping into channels 43 of panels 13. Panel 17 may be formed at its lower end with a cut-out 70 to fit an opening in the furnace. The cut-out 70 has side edges 71.

Fitted over the top of the casing is the cover 18 which may have a top wall 73 and an annular skirted flange 74, which fits over the upper edges of panels 12, 13 and 14. The cover 18 aids in keeping the panels in cylindrical shape.

The base band 19 may be made of a pair of normally straight strips 80, 81. Said strips may have bent back hooks or flanges 82 at their inner ends to receive a short clip or coupling member 83. The coupling member 83 has a back wall or web 84 and inwardly extending flanges 85 engaging the flanges 82. In other words, member 83 is similar to the clips 36 except that it is of shorter length.

At the outer ends of the strips 80, 81 are bent back hooks 86, which may engage the edges 71 of panel 17 at the cut-out 70.

In Fig. 14 there is shown a modified construction for use with a cylindrical boiler formed with a box-like projecting panel. In Fig. 14 there is shown a casing 10a, which may be similar to casing 10 except that substituted for one of the rear panels 14, 15, 16 or 17 is a casing member 90 of

sheet metal and having horizontal top and bottom walls 91, parallel vertical side walls 92, and a front wall 93 formed with a rectangular opening 94. The inner edges of the top and bottom walls 91 are arcuate to fit the cylindrical casing. The projecting casing portion on the boiler may project into the casing part 90. The side walls 92 may be formed at their rear ends with bent back flanges 98 assembled to the side panels 13 by coupling members 36.

It will be noted that the panel parts may be shipped flat in a compact package together with the cover. The parts may be readily assembled where the boiler is located in a relatively few minutes, and in so doing, the flat panels are merely flexed or sprung into curved shape. The panels are held in such shape due to the assembly. It is not necessary to roll any of the panels into round shape. Furthermore, the casing may be very easily disassembled should it be necessary to put a new insulating blanket on the boiler or if any repairs are to be made. The panels may have pre-cut openings and cut-outs to fit a particular boiler. The casing does not have to be shipped in assembled condition or assembled with the boiler before shipping the boiler. In fact, no panels have to be shipped in curved shape. While sheet aluminum has been found highly desirable for making casings of the type described herein, sheet steel and other flexible and resilient sheet metal may be employed.

In Fig. 15 is shown a casing 10b of modified construction embodying the invention. The same comprises a front panel 12 to which is interconnected side panels 13 by means of coupling members or clips 36, as previously described. One or more rear panels 100 comprising a one piece sheet of resilient metal is formed with right angle longitudinal flanges 101, 102 at the outer side edges thereof. The same may be flexed into round shape and into the channels 43 of side panels 13. The panel or panels 100 may be formed with suitable openings which will fit around pipes or the like extending from the boiler or into the boiler. The lower end of the lowermost panel 100 may be provided with a cut-out such as shown in panel 17, in Fig. 13.

In Fig. 16 is shown a further modification 10c of the casing embodying the invention. The same comprises a one piece rear panel 105 of resilient sheet metal formed with right angle longitudinal flanges 106, 107 on the outer side edges thereof. There is further provided a one piece front panel 108 of resilient sheet metal formed with integral longitudinal U-shaped offset portions 110 on the outer side edges thereof. The rear panel 105 may be flexed into a curved member slightly less than a semi-circle and the front panel may be flexed into a curved member slightly greater than a semi-circle, with its edge portions 110 receiving the flanges 106, 107 of panel 105 to form a cylindrical casing. The panels 105 and 108 may be provided with suitable openings to admit pipes and the like extending from or into the boiler which is encased in the casing. The U-shaped portions 110 and the offset flanges 106, 107 project radially inwardly of the assembled casing.

In Fig. 17 is shown a further modification 10d of the casing embodying the invention and adapted to be used with boilers having projections extending from front or side portions thereof. A casing member 90 similar to that shown in Fig. 14 except as hereinafter described is adapted to be used in lieu of selected portions or part of the side panels 13. The member 90 includes par-

allel side walls 92, one side wall being formed with a bent back flange 98 and the other side wall with a U-shaped portion 40, and interconnected to front panel 12 by a coupling member 36, and to the rear panel of the casing by receiving the side flange thereof in portion 40.

If desired, the member 90 may replace part of the front panel in which event both of its side walls will be provided with bent back flanges to receive clips 36 for assembling the same with the side panels.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described our invention, we claim as new and desire to protect by Letters Patent of the United States:

1. A sectional casing for a boiler or the like, comprising an annular wall consisting of a plurality of vertically extending readily detachable panels formed of resilient sheet metal, said panels being initially flat and being bowed transversely below their elastic limit to form transversely curved sections of a casing that is annular in cross-section, the bowed panels having a tendency to return to their completely flattened condition, abutting side edges of said panels being bent to form joint sections disposed in interfitting engagement with each other and detachably held together by frictional grip exerted by the tendency of the panels to return to the flattened condition.

2. A sectional casing for a boiler or the like, comprising an annular wall consisting of a plurality of vertically extending readily detachable panels formed of resilient sheet metal, said panels being initially flat and being bowed transversely to form transversely curved sections of a casing that is annular in cross-section, the bowed panels having a tendency to return to flat condition, and joints for said panels comprising radially interfitting flange and channel means at the meeting longitudinal side edges of adjacent panels to detachably hold said panels together, said interfitting means being frictionally clamped by the tendency of the panels to return to a fully flattened condition.

3. A sectional casing for a boiler or the like, comprising an annular wall consisting of a plurality of vertically extending readily detachable initially flat panels of resilient sheet metal, said panels being transversely bowed to form curved sections of a casing that is annular in transverse cross-section, said panels having a tendency to return to a completely flattened condition, means to detachably interconnect adjoining end of adjacent bowed panels, said means comprising an inwardly extending, outwardly opening, integral channel at the longitudinal edge of one panel, and an inwardly extending flange integral with and extending along the longitudinal edge of the adjacent panel and received within said channel and frictionally gripped therein by the tendency of said panels to return to their normally flat condition.

4. A sectional casing for a boiler or the like, comprising an annular wall consisting of a plu-

rality of vertically extending readily detachable panels formed of resilient sheet metal, said panels being initially flat and being bowed transversely below their elastic limit to form transversely curved sections of a casing that is annular in cross-section, said panels having a tendency to return to their completely flattened condition, abutting side edges of said panels being bent to form joint sections disposed in interfitting engagement with each other and so held by frictional grip exerted by the tendency of the panels to return to the flattened condition, and a cover resting upon end edges of the panels and having a depending marginal flange fitting closely about the annular wall and bracing the wall.

5. A casing for a boiler or the like, comprising an annular wall consisting of a plurality of vertically extending readily detachable panels formed of resilient sheet metal, said panels being initially flat and being bowed transversely below their elastic limit to form transversely curved sections of a casing that is annular in cross-section, the bowed panels having a tendency to return to their completely flattened condition, abutting side edges of said panels being bent to form joint sections disposed in interfitting engagement with each other and detachably held together by frictional grip exerted by the tendency of the panels to return to the flattened condition, and a cover resting upon upper edges of the panels and having a depending marginal flange fitting closely

about the annular wall and bracing the wall, a pair of said panels being formed with complementary cut-outs at a joint section to form an opening for receiving a member extending from said boiler.
